CLAIM

The ornamental design for a divided tray, as shown and described.

DESCRIPTION

FIG. 1 is a top plan view of a divided tray showing my new design;

FIG. 2 is a front elevational view, the rear, left and right side elevational views being identical thereto;

FIG. 3 is a bottom plan view thereof;

FIG. 4 is a sectional view taken along line 4—4 of FIG. 1; and,

FIG. 5 is a top plan view of a divided tray showing a second embodiment of my design in which the views not shown would derive from FIGS. 2-4.

FIG. 1***FIG. 2******FIG. 3******FIG. 4****FIG. 5*
